LIQUID FUEL BURNER APPARATUS

Edwin I. Kraber, York, Pa., assignor to York Oil
Burner Co., Inc., York, Pa., a corporation of
Delaware

Application November 9, 1939, Serial No. 303,697

6 Claims. (Cl. 158—28)

This invention relates to liquid fuel burner apparatus, and more particularly to the arrangement of and support for electric ignition leads positioned within a controlled air supply conduit or passage. The holder or support is particularly adapted for use in cooperation with air flow controlling devices of the iris diaphragm type, as shown, for example, in the patent to James D. Lalor #2,037,663, granted April 14, 1936.

10 Liquid fuel burners of the spray type having an oil pipe and nozzle arranged centrally within a surrounding combustion air supply conduit are known. The use of electric spark ignition at a gap adjacent the oil nozzle is also known. It is an object of this invention to provide an improved insulating support for electric ignition leads within an air supply conduit having an iris diaphragm flow regulator. It is an object of this invention to provide a support of the character described which results in minimum interference with a controlled flow of combustion air through such a supply conduit.

15 It is the further object of this invention to provide an ignition lead insulating support of small size adapted to be positioned on and carried by a fuel supply pipe where the pipe and ignition leads pass through an iris type air valve.

20 A further object is the provision of an insulating support of the character described the surfaces of which assure ample creepage distances for minimizing leakage or surface discharge of the high tension ignition current between the leads and the pipe, or between the leads and adjacent air valve devices.

25 Other objects and advantages of this invention will be apparent from the following description of the embodiment of the invention illustrated in the accompanying drawing in which:

30 Figure 1 is a plan view, partly in section, of the furnace end of a spray or gun type liquid fuel burner having an ignition lead support constructed in accordance with my invention.

35 Figure 2 is an elevation view, partly in section, of a portion of the apparatus shown in Figure 1.

40 Figure 3 is a sectional view on line 3—3 of Figure 1.

45 Referring to Figure 1 of the drawing, the fuel nozzle of a liquid fuel burner device is indicated by the numeral 10. The nozzle 10 is at the furnace end of a fuel supply pipe 11, the latter being centrally arranged and supported within an air supply conduit or tube 12. The air conduit 12 is connected by coupling flanges 13 and 14 to the outlet 15 of an air blower or fan not shown. The

5 fuel pipe 11 near its forward end may be supported centrally within the air conduit 12 by a stationary air spiral or spider device 16 having feathered arms 17 to impart any desired whirling motion to the forced air supply as it approaches the burner nozzle.

10 An adjustable iris diaphragm 18 is provided for controlling the character and volume of air flow within the conduit 12. The diaphragm 18 may be mounted in the coupling flanges 13 and 14, and is provided with adjusting mechanism including a slotted ring 19 and an external handle 20 whereby the size of the diaphragm opening may be regulated to increase or decrease the flow of air. The use of any form of iris diaphragm air valve is contemplated, and the 15 constructions shown in the drawing and in the above mentioned Lalor patent are examples of satisfactory air control devices.

20 An electric spark gap for ignition purposes is indicated by the numeral 21. High tension current is conducted to the gap by a pair of metal leads or buss bars 22. The leads 22 may be supported adjacent the spark gap by a pair of insulating bushings 23 of porcelain or the like 25 secured in or to the arms or blades 17 of the spider 16. The central ignition lead holder or support is indicated by the numeral 24 and is formed of porcelain or other insulating material. The holder 24 extends through the diaphragm 30 opening and is positioned on the fuel pipe 11, which latter extends through the central bore of the holder. The outer surface of the ignition lead holder 24 is preferably smooth and may be 35 symmetrically tapered or streamlined at each end to minimize interference with the desired flow of combustion-supporting air through the adjustable opening of the diaphragm 18. The cross-section of the holder 24 at the diaphragm may be somewhat oval, as shown, to accommodate the leads 22 at opposite sides of the fuel pipe, or it may be cylindrical. Each end of the central bore through the holder 24 is preferably 40 counterbored or recessed, as shown in dotted lines in Figure 1, to increase the creepage distance between the entrance of the lead 22 into the outer surface of the holder 24 and the contact of the holder with the fuel pipe 11. Sufficient 45 creepage distance, usually two or more inches, may thus be provided in a short holder 50 to avoid loss or discharge of the high tension current from the leads to the fuel pipe. The iris diaphragm 18 is preferably arranged so that it cannot be closed enough to contact with the outer surface of the holder 24, and hence the 55

possibility of creepage loss between the leads 22 and the diaphragm segments is also avoided.

In the operation of spray type liquid fuel burners of the character shown, a smooth flow of combustion-supporting air to the air spiral or blades 17 increases the burner efficiency and diminishes losses due to excessive air agitation and pressure fluctuations in the supply conduit. The use of the iris type diaphragm to control air flow 10 diminishes air stratification and agitation, and restricts the size of the air passage evenly on all sides, as distinguished from the effect of vane or gate type air valves. The novel ignition lead holder herein described has been found to aid in 15 avoiding excessive air agitation and pressure fluctuation because its air-flow or streamline contour has minimum disturbing action on the smooth flow of air through the restricted iris opening surrounding the holder. The holder described 20 may be relatively short and still provides adequate insulation for the high tension leads, because of its counter-bored ends and its spacing from the air valve parts.

It is to be understood that this invention is 25 also applicable to liquid fuel burners of other types, such, for instance, as pan, tray and retort burners.

Other advantages of my improved apparatus will be readily apparent from the above description 30 thereof. Obviously, variations in the nature and arrangement of the elements described will be evident to those skilled in this art, and this invention contemplates any equivalent structure within the scope of the following claims.

35 Having described my invention, what I claim and desire to secure by Letters Patent is:

1. In liquid fuel burner apparatus, the combination comprising, an air supply conduit, an iris diaphragm valve in said conduit for regulating 40 the air flow therethrough, a fuel supply pipe supported within said conduit and passing through said valve, electric ignition leads within said conduit, an insulating holder for said ignition leads supported on said pipe and extending through 45 said valve, said holder having a relatively smooth outer surface to minimize interference with the flow of air through said conduit under control of said diaphragm valve.

2. In liquid fuel burner apparatus, the combination comprising, an air supply conduit, a 50 iris diaphragm valve in said conduit for regulating the air flow therethrough, a fuel supply pipe supported within said conduit and passing through said valve, electric ignition leads within said conduit, an insulating holder for said ignition leads supported on said pipe and extending through said valve, said holder being formed of refractory insulating material and having a relatively 55 smooth outer surface tapering inwardly toward the ends to provide a streamline contour for minimizing interference with the flow of air through said conduit under the control of said diaphragm valve.

3. In liquid fuel burner apparatus, the combination comprising, an air supply conduit, an iris diaphragm valve in said conduit for regulating the air flow therethrough, a fuel supply pipe supported within said conduit and passing through 5 said valve, electric ignition leads within said conduit, an insulating holder for said ignition leads supported on said pipe and extending through said valve, said holder being formed of insulating material and having counterbored ends of a 10 diameter greater than the outer diameter of the fuel supply pipe to provide added creepage distance between the ignition leads and the fuel supply pipe, said holder having a smooth outer surface of streamline contour for minimizing interference with the flow of air through said conduit under the control of said diaphragm valve. 15

4. In liquid fuel burner apparatus, the combination comprising, an air supply conduit, an iris diaphragm valve in said conduit for regulating the air flow therethrough, a fuel supply pipe supported within said conduit and passing through 20 said valve, electric ignition leads within said conduit, an insulating holder for said ignition leads supported on said pipe and extending through 25 said valve, said holder having a central axial bore for said fuel supply pipe and having longitudinal passages on opposite sides of said central bore for said ignition leads, the outer surface of said holder being substantially smooth and with oppositely 30 tapered ends to provide streamline contour for minimizing interference with the flow of air through said conduit under the control of said diaphragm valve.

5. In liquid fuel burner apparatus, the combination comprising, an air supply conduit, an iris diaphragm valve in said conduit for regulating the air flow therethrough, a fuel supply pipe supported within said conduit and passing through said valve, electric ignition leads within 40 said conduit, an insulating holder for said ignition leads supported on said pipe and extending through said valve, said holder being approximately oval in cross-section where it extends through said valve and having a relatively smooth 45 outer surface to minimize interference with the flow of air through said conduit under control of said diaphragm valve.

6. In liquid fuel burner apparatus, the combination comprising, an air supply conduit, a 50 diaphragm valve positioned in said conduit for controlling the air flow therethrough, a fuel supply pipe supported within said conduit and passing through said diaphragm valve, electric ignition leads within said conduit, an insulating holder for said ignition leads supported on said pipe and extending through said diaphragm valve, said holder having a relatively smooth outer surface to minimize interference with the flow of air through said conduit under control of said 55 diaphragm valve.

EDWIN I. KRABER.
